KNITTING MACHINE COMPANY, OF PAWTUCKET, RHODE ISLAND, A CORPORA-
TION OF RHODE ISLAND.

NEEDLE-CONTROLLING MECHANISM FOR KNITTING MACHINES.

Application filed January 8, 1919. Serial No. 270,191.

To all whom it may concern:

Be it known that I, MAX C. MILLER, a citizen of Germany, residing at Cumberland Hill, in the county of Cumberland and State 5 of Rhode Island, have invented certain new and useful Improvements in Needle-Controlling Mechanism for Knitting Machines; and I do hereby declare the following to be a full, clear, and exact description of the invention, such as will enable others skilled in 10 the art to which it appertains to make and use the same.

The invention relates to needle controlling mechanism for knitting machines.

15 One of the features of the invention contemplates the provision of means for pressing forward at the yarn feeding point the hook ends of a series of needles distributed among the entire knitting series of needles 20 to divide the needles into two sets or series, one of which is in and the other of which is out of yarn taking relation to the yarn feeding means, so that yarn is fed to but one set of needles by the co-operating yarn 25 feed.

Another feature, which may be utilized with or without the feature outlined above, 30 contemplates controlling the action of some or all of the needles of a needle series by a series of needle deflectors arranged to act on the backs of the needles, and successively advanced to press or bend forward the corresponding needles by actuating means such for instance as a cam, which may be thrown 35 into and out of action during the knitting, and which acts progressively along a series of deflectors by reason of the relative travel between the actuating means and deflectors. By throwing the actuating means for the 40 needle deflectors into and out of action, the operation of the needles may be varied at different points in the knitting, in accordance with the results which it may be desired to obtain.

45 Another feature of the invention, which may be utilized with or without either or both of the features outlined above, contemplates the provision of a plurality of 50 series of needle deflectors for acting on and pressing forward different series of needles distributed among the entire series. Means is preferably provided for selectively actuating the different series of needle deflectors, and this means preferably consists of a se-

ries of actuators, each of which acts on a 55 different series of deflectors, which are so controlled that any series or combination of series of needle deflectors may be actuated during any desired part of the knitting.

A construction embodying all the features 60 of the invention is shown in the drawings, in which Figure 1 is a plan view of so much of the knitting head of a circular machine as is necessary to show the application of the invention thereto, the parts above 65 the upper end of the needle cylinder being removed; Fig. 2 is a vertical sectional view through the head on line 2, Fig. 1; Fig. 3 is a detail plan view indicating the feed of 70 the yarn to the needles; and Fig. 4 is a detail elevation looking toward the left in Fig. 2.

In the drawings the invention is shown as applied to a circular latch needle machine of the type used for knitting seamless 75 hosiery. As shown, the needle cylinder 1 of the machine is provided at its lower end with a gear 2, through which rotary and reciprocatory motion may be transmitted to the cylinder. The cylinder is provided with the usual vertical grooves in which the latch needles 3 are mounted. The knitting wave in the needles is formed by the usual knitting cams which are indicated generally at 4, and the machine is provided with the 80 usual cams and pickers for actuating the needles to knit seamless hosiery. The machine is also provided with a latch ring 5 having a feeding throat 6 through which the yarns may be fed to the needles by a 85 series of yarn changer guides, one of which is indicated at 7. A yarn guide, indicated at 8, may be provided for properly feeding the body yarn to the needles through a 90 guideway 9 in the throat when doing plated 95 work.

In the machine shown, all the features of the invention are embodied in a mechanism for pressing forward certain selected needles as they pass the yarn feeding point of the 100 knitting wave, so that yarn is fed to some of the needles and not to others by the yarn feeding guide or guides 7. The means for pressing forward the needles comprises one or more series of needle deflectors, preferably 105 in the form of sliding pins 10, which are arranged to act on the backs of a series of needles distributed among the entire se-

ries of needles. In the construction shown there are seven series of needle deflecting pins, and they are mounted in seven series of pin holes 11 formed in the needle supporting cylinder, one above the other, as indicated in Fig. 2. In fine gage machines it will be found desirable to stagger the needle holes in adjoining series, and to arrange the holes in each series to register with alternate needles. The needle deflecting pins are differently distributed in the different series of pin holes, according to the desired effects to be produced in the knit fabric. A separate actuator in the form of a cam 12 is preferably provided for forcing forward each series of pins as they are carried past the cam by the rotation of the needle cylinder. Means is provided for throwing each actuator cam into or out of action, so that any series of deflector pins, or any combination of different series may be actuated to press forward corresponding series of needles. As shown, the cams 12 are formed on a series of cam levers 13 which are pivotally mounted one above the other in a supporting ring 14 arranged within the needle cylinder. The ring fits within the needle cylinder, and is supported by a series of screws 15, the inner ends of which are arranged to engage a ledge on the cylinder. The cams 12 are formed on the outer sides of the levers 13, and are arranged one above the other, so that they act to force forward the different needle deflecting pins at the same point with relation to the yarn feeding guide. The cam levers 13 are provided on their rear sides with a series of cam lugs 16 arranged to be engaged by a series of vertically sliding controller rods 17 which are guided in a bracket 18 secured to the base plate of the machine. The lower ends of the controller rods engage the horizontal arms of a series of bell crank levers 19, the vertical arms of which are arranged to be engaged by horizontal rods 20. These rods may be actuated by any suitable pattern mechanism to automatically control the throwing in and out of the cam levers 13 during the knitting. The ring 14 is held in position during the rotation of the needle cylinder by the engagement of a lug 21 with one arm of a bell crank lever 22, the other arm of which bears against an adjusting rod 23. The lower end of the rod rests on the head of an adjusting screw 24, which is locked in adjusted position by a lock screw 25.

Assuming that yarns are being fed to the knitting wave while producing plated work, the body yarn being fed through the yarn guide 8, and the plating yarn which normally appears on the outside of the fabric being fed to the needles by the guide 7, and assuming that the yarn guide 7 is arranged as shown in the drawings, and that the series of needle deflecting pins corresponding to the cam 12 which is in active position are arranged to force forward every other needle, then the operation will be as follows. The needles which are forced forward are so deflected from their normal position with relation to the yarn guide 7 that the yarn will pass back of these needles and will not therefore be taken and knit by them. The yarn will however be presented in the usual way to the needles which are not pressed forward, and will be knit by them. The body yarn will be fed to all the needles, and will be knit by the needles which were forced forward and did not knit the plating yarn, as well as by the needles which knit the plating yarn. If the second or body yarn is of a different color from the first or plating yarn, a design will be produced in which the body yarn will show on a ground of plated fabric at the points where knit by the needles which are pressed forward and which did not knit the plating yarn. By varying the cam or cams 12, which are in active position, a great variety of fancy fabrics, such as vertical or zigzag stripes, checks, diamonds, etc. may be produced. By changing the yarns at different points in the knitting, a further variation in the designs produced may be effected.

Instead of utilizing a mechanism such as shown and described for producing various designs in plated fabrics, a series of needle deflectors, actuated by a cam or other actuator which may be thrown into and out of action during the knitting, may be utilized in feeding an extra or supplemental yarn to every other needle, or to a selected series of needles distributed among the needles to which the main yarn is fed, and the extra or supplemental yarn may be fed to the selected series of needles during one or several successive courses at different points in the fabric.

The mechanism above described may be utilized to press the needles forward out of normal relation to the yarn feeding guide or guides 7 to vary the number and distribution of the needles which take yarn and knit during any course or courses of the knitting, and thus the character and appearance of the stitches formed may be varied to secure various designs of fabric.

While the invention has been shown and described as embodied in a mechanism for forcing needles outward at the yarn taking point, it will be understood that various features of the invention are not confined in their application to forcing the needles outward for this purpose, but may be utilized for forcing outward series of needles distributed among the entire series of needles for various purposes. It will also be understood that although in the application of the invention illustrated the series of actuator

cams for the needle deflectors are arranged to deflect each series at the same point, such arrangement is not essential, and may be varied in accordance with the type of machine in which the invention is embodied, and in accordance with the purpose for which it is utilized.

It will also be understood that the invention is not confined in its application to 10 circular machines, or to latch needle machines, but may be utilized with advantage in other types of machines, such as dial or straight bar machines, and may be utilized to press forward and control the action of 15 spring needles as well as latch needles.

What is claimed is:—

1. A knitting machine, having, in combination, a series of needles, yarn feeding means, a series of needle deflectors for forcing forward the yarn taking ends of an 20 equal number of needles distributed among the needle series to divide the needles into two sets, one of which is in and the other of which is out of yarn taking relation to 25 the feeding means and means for successively actuating the deflectors.

2. A knitting machine, having, in combination, a series of needles, a yarn guide, a series of needle deflectors arranged to act on 30 the backs of a series of needles equal in number to the number of deflectors and distributed among the needle series, and an actuator for successively actuating the needle deflectors at the feeding point to force the yarn 35 taking ends of the corresponding needles forward with relation to the remaining needles of the needle series.

3. A knitting machine, having, in combination, a yarn feeding guide, a series of independently operated needles, means for 40 forming a knitting wave in the series, a series of needle deflectors arranged to act on the backs of an equal number of needles distributed among the needle series and to force 45 the yarn taking ends of the corresponding needles forward, and an actuator for successively actuating the needle deflectors at the yarn feeding point.

4. A knitting machine, having, in combination, a yarn feeding means, a needle cylinder, a continuous series of needles carried by the cylinder, a series of radially movable deflectors carried by the needle cylinder 50 within the series of needles and arranged to act on the backs of a series of needles distributed among the needle series, and an actuator within the series of deflectors for actuating the deflectors at the feeding point.

5. A knitting machine having, in combination, a series of needles, a series of needle deflectors arranged in permanent alinement with needles in the needle series to act on 60 their backs and deflect them transversely of the series, means for actuating the deflectors 65 arranged to act progressively along the se-

ries, and mechanism for rendering said means active or inactive during the continuance of the knitting.

6. A knitting machine, having, in combination, a series of needles, a series of needle deflectors arranged to act on the backs of needles in the needle series and deflect them transversely of the series, and a cam for advancing the deflectors arranged to act progressively along the series and movable into 70 or out of inactive relation to the deflectors during the continuance of the knitting.

7. A knitting machine, having, in combination, a series of needles, a plurality of series of needle deflectors arranged to act on 80 the backs of equal numbers of needles distributed among the needle series, and means for selectively actuating the different series of deflectors during the knitting to successively press forward the corresponding series of needles.

8. A knitting machine, having, in combination, a series of needles, a plurality of series of needle deflectors arranged to act on the backs of equal numbers of needles 90 distributed among the needle series, and an actuator for each series of deflectors for successively actuating the corresponding series of deflectors during the knitting.

9. A knitting machine, having, in combination, a series of needles, a plurality of series of needle deflectors arranged to act on equal numbers of needles distributed among the needle series, a series of actuators for the deflectors arranged to actuate each series 100 at the same point, and means for selectively rendering the actuators active and inactive.

10. A knitting machine, having, in combination, a needle support provided with needle grooves, a series of forwardly movable pins in the support back of and registering with the grooves, a cam for successively advancing the pins at a predetermined point, and mechanism for rendering the cam active or inactive during the knitting.

11. A knitting machine, having, in combination, a needle support provided with needle grooves, several series of forwardly movable pins in the support back of and registering with different series of grooves 115 distributed among the entire series of grooves and means for selectively actuating the different series of pins.

12. A knitting machine, having, in combination, a needle support provided with 120 needle grooves, several series of forwardly movable pins in the support back of and registering with different series of grooves distributed among the entire series of grooves, and a corresponding series of cams 125 for advancing the different series of pins.

13. A knitting machine, having, in combination, a needle support provided with needle grooves, several series of forwardly movable pins in the support back of and 130

registering with different series of grooves distributed among the entire series of grooves, a corresponding series of cams for advancing the different series of pins, and 5 means for rendering the cams selectively active or inactive during the knitting.

14. A knitting machine, having, in combination, a needle support provided with needle grooves, needles mounted in the 10 grooves, a series of needle deflectors mounted in the support back of and in alinement with a corresponding series of needles, means for progressively actuating the deflectors to press forward the corresponding series of 15 needles, and mechanism for rendering said actuating means active or inactive during the continuance of the knitting.

15. A knitting machine having, in combination, a needle support provided with 20 needle grooves, needles mounted in the grooves, a series of needle deflectors mounted in the support back of and in permanent alinement with a corresponding series of needles and distributed among the needle 25 series to divide the needles into two sets, means for progressively actuating the deflectors to force forward the yarn-taking ends of the corresponding series of needles, and mechanism for rendering the actuating 30 means active or inactive during the continuance of the knitting.

16. A knitting machine having, in combination, a series of needles, yarn feeding means, a series of needle deflectors each 35 mounted in permanent alinement with a needle to force forward its yarn taking end and distributed among the needle series to divide the needles into two sets, one of which is in and the other of 40 which is out of yarn taking relation to the

feeding means, and means for successively actuating the deflectors.

17. A knitting machine having, in combination, a needle support provided with needle grooves, needles mounted in the 45 grooves, a series of needle deflectors each mounted in permanent alinement with a needle to act on its back and press it forward, means for progressively actuating the deflectors, and mechanism for rendering said 50 means active or inactive during the continuance of the knitting.

18. A knitting machine having, in combination, a needle support, a series of needles mounted to reciprocate in the support, means 55 for forming a knitting wave in the needles, yarn feeding means, a series of needle deflectors each mounted in permanent alinement with a needle to act on its back below the knock-over point and distributed 60 among the needle series to divide the needles into two sets, one of which is in and the other of which is out of yarn taking relation to the feeding means, and means for successively actuating the deflectors. 65

19. A knitting machine having, in combination, a needle support, a series of needles, means for forming a knitting wave in the 70 needles, yarn feeding means, a series of needle deflectors each mounted in permanent alinement with a needle to act on its back below the knock-over point and deflect it transversely of the series, means for progressively actuating the deflectors, and mechanism for rendering said means active 75 or inactive during the continuance of the knitting.

MAX C. MILLER.
